UNITED STATES PATENT OFFICE

2,038,423

APPARATUS FOR USE IN APPLYING
SHOE BOTTOM FILLER

Charles F. Eaton, West Newbury, Mass., assignor, by mesne assignments, of one-half to North American Holding Corporation, Syracuse, N. Y., a corporation of New York, and one-half to Parshad Holding Corporation, Syracuse, N. Y., a corporation of New York

Application July 19, 1935, Serial No. 32,220

9 Claims. (Cl. 18—1)

This invention relates to an apparatus for use in applying filler material to the bottom of the foreparts of shoes preparatory to the application of the outsoles.

5 The principal objects of the invention are to provide a convenient means for holding a supply of filler material in a position where it is readily accessible to the operator of the press, and to provide an improved means for attaching the apparatus to a press mechanism, which means is universally adjustable so that the filler material may be readily available and quickly transferred without lost motion on the part of the operator.

Further objects relate to various features of 15 construction and will be apparent from a consideration of the following description and the accompanying drawings, wherein:

Fig. 1 is a front elevation of a press and an apparatus constructed in accordance with the 20 present invention;

Fig. 2 is a side elevation of the apparatus shown in Fig. 1;

Fig. 3 is a fragmentary side elevation of the 25 pedestal of the press to which the apparatus is attached;

Fig. 4 is a front elevation, with parts broken away and shown in section, of the cradle and associated parts;

Fig. 5 is a section on the line 5—5 of Fig. 1;

Fig. 6 is a plan view of the cradle and associated parts; and

Fig. 7 is an elevation of the adjusting device.

Referring to Figs. 1 and 2, the press to which my apparatus is attached may be of the type 35 shown in Patent No. 1,927,279, dated September 19, 1933, which comprises a base 10 supported on a pedestal or stanchion 11 which rests upon a floor or like support. Mounted on the base 10 is a shoe pressing roll 12, a rocking press head 14 and press actuating mechanism 15, these parts being of the construction shown in the above mentioned patent to which reference may be had for a more detailed description.

The pedestal 11 is provided with a bracket 20 45 having a vertically extending arm 21, the bracket 20 preferably being secured to the stanchion 11 by bolts 18 which extend through vertical slots in the pedestal, thus providing means permitting the vertical adjustment of the bracket relative to the floor or other support on which the pedestal rests. A laterally extending arm 23 is bolted or otherwise rigidly secured to the arm 21 and at its outer end is provided with an enlarged portion having a substantially vertically extending bore 50 55 24 (Figs. 4 and 6). A yoke 25 is mounted for

5 pivotal movement about the end of the arm 23 and to this end the arms 26 and 27 (Figs. 1 and 4) of the yoke are provided with vertically aligned openings registering with the bore 24 which receives a pintle 28 having its upper and lower ends 5 projecting into openings in the arms of the yoke, as shown in Fig. 4. The pintle 28 is locked within the bore 24 by a pin 29 or in any other suitable manner and one of the arms 26 of the yoke is provided with a threaded aperture for the reception 10 of a locking bolt 30 by means of which the yoke may be locked in any desired position of adjustment about the pintle 28.

A bracket 32 which is preferably of a generally triangular shape is pivotally mounted on the 15 outer face of the yoke 25 by means of a pivot bolt 33 which extends through an opening in the upper end of the body of the yoke into a threaded aperture in the apex of the bracket, as shown in Fig. 4. The lower end of the bracket 32 is provided with an arcuate slot 34 (Figs. 2, 5 and 7) which conforms to the curvature of a circle concentric with the axis of the pivot bolt 33. A clamping bolt 35 extends through the slot 34 20 into a threaded aperture in the lower end of the yoke 25 and a washer 36 is interposed between the head of the bolt 35 and the outer face of the bracket 32 as shown in Figs. 1 and 4. A lever or operating handle 38 is longitudinally secured in any suitable manner to the head of the bolt 35. 25 By swinging the handle 38 in one direction or the other the clamping bolt may be released or locked and the bracket 32 may then be swung to any desired position and locked in the adjusted position. 30

An extension 40 is formed integral with the bracket 32, this extension having an arcuate flange to which is bolted or otherwise rigidly secured a cradle 42. As here shown by way of illustration the cradle is semi-circular in shape and is 35 preferably of a grille-like construction, having at its rear an inwardly extending flange 43 which provides an abutment for the bottom of a container C disposed in a cradle. On the bottom wall 40 of the cradle and adjacent to the flange 43, an upstanding boss 44 (Fig. 6) is formed, and at a corresponding location on the rear walls of the cradle inwardly projecting lugs 45 and 46 are formed. The boss 44 and lugs 45 and 46 are 45 constructed and arranged to engage the annular rim at the bottom of the container and thus hold it in position within the cradle, as shown in Fig. 5. The front end of the cradle is provided with an upstanding arcuate flange 48 (Figs. 5 and 6) 50 55

which holds the container in a slightly inclined position relative to the cradle.

A tray or shelf 50 is pivotally connected at 51 to the front end of the cradle so as to swing about a horizontal axis. The edges of the tray are provided with upstanding side walls which define an enclosure adapted to contain a quantity of filler material scooped out from the container. One end of a tray-supporting link 52 is pivotally connected at 53 to the front end of the cradle and its opposite end is provided with a longitudinally extending slot 54. A thumb screw 55 extends through the slot 54 into a threaded aperture in the side wall 56 of the tray. The screw 55 having a flanged head which is operative to clamp the link 52 against the wall 56, thereby to hold the tray in any desired position of adjustment, as shown in Fig. 2.

In using an apparatus constructed in accordance with the present invention, a fully loaded or a partly loaded container is placed within the cradle so that the wall of the container is supported at its front end by the flange 48 and at its rear by the boss 44 and lugs 45 and 46 which serve to hold the rim of the container in position against the rear flange 43. Either before or after placing the container in the cradle its vertical position, that is, its distance from the floor, may be adjusted by loosening the bolts which secure the bracket 20 to the pedestal 11 and sliding the bracket upwardly or downwardly to the desired horizontal position and then tightening the bolts to hold the bracket 20 in its adjusted position. The angle of the cradle in a horizontal plane may be adjusted by swinging the yoke about the pintle 28 and locking it in the adjusted position and in a similar manner the angle of the cradle in a vertical plane may be adjusted by swinging the bracket 32 about the pivot bolt 33 to any desired angle of inclination and locking it in position by means of the clamping bolt 35. In this manner the position of the cradle may be adjusted as best suits the convenience of the operator.

In applying filler material to boots or shoes the operator, using a trowel or spatula, scoops a quantity of the filler material from the container into the tray 50 and from time to time he transfers gauged amounts of the material from the tray to the boots or shoes to be filled. After depositing a small quantity of the material upon the insole of a boot or shoe, it is transferred to the press roll 12 where it is positioned below the vertically reciprocating platen of the press head 14 by means of which the filler material is distributed throughout the cavity of the shoe and properly leveled. The entire operation may be carried out by the operator without changing his position once the cradle has been adjusted to the position which best suits his convenience.

While I have shown and described one desirable embodiment of the invention it is to be understood that this disclosure is for the purpose of illustration only and that various changes in shape, proportion and arrangement of parts, as well as the substitution of equivalent elements for those herein shown and described, may be made without departing from the spirit and scope of the invention as set forth in the appended claims.

I claim:

1. The combination with a shoe filler press having filler leveling mechanism and an upright supporting member, of an apparatus for holding shoe filler material in a position adjacent to said

leveling mechanism, said apparatus comprising a bracket secured to said supporting member, a cradle for holding a container of filler material, said cradle being mounted on said bracket for pivotal movement about horizontal and vertical axes, and a shelf secured to the front of said cradle and arranged in a position to receive filler material scooped from said container. 5

2. The combination with a shoe filler press having filler leveling mechanism and an upright supporting member, of an apparatus for holding shoe filler material in a position adjacent to said leveling mechanism, said apparatus comprising a bracket mounted for vertical movement along said upright, clamping means for locking said bracket 10 in any selected position of adjustment along said upright, a cradle for holding a container of filler material, said cradle being mounted on said bracket for pivotal movement about horizontal and vertical axes, and a shelf secured to the front 15 of said cradle and arranged in a position to receive filler material scooped from said container.

3. The combination with a shoe filler press having filler leveling mechanism and an upright supporting member, of an apparatus for holding shoe 20 filler material in a position adjacent to said leveling mechanism, said apparatus comprising a bracket secured to said supporting member, a yoke pivotally secured to said bracket, a cradle for holding a container of filler material, said cradle 25 being mounted on said yoke for pivotal movement about an axis at right angles to the pivotal axis of said yoke, and a shelf secured to the front of said cradle in a position to receive filler material scooped from said container. 30

4. The combination with a shoe filler press having filler leveling mechanism and an upright supporting member, of an apparatus for holding shoe 35 filler material in a position adjacent to said leveling mechanism, said apparatus comprising a bracket secured to said supporting member, a yoke mounted on said bracket for pivotal movement about a vertical axis, a cradle for holding a container of filler material, said cradle being supported on said yoke and pivotally mounted to 40 swing about a horizontal axis, and a shelf secured to the front of said cradle in a position to receive filler material scooped from said container. 45

5. The combination with a shoe filler press 50 having filler leveling mechanism and an upright supporting member, of an apparatus for holding shoe filler material in a position adjacent to said leveling mechanism, said apparatus comprising a bracket secured to said supporting member, a 55 cradle for holding a container of filler material, said cradle being mounted on said bracket for pivotal movement about horizontal and vertical axes, positioning means carried by said cradle and engageable with said container to hold it 60 firmly in position for any position of adjustment of said cradle, and a shelf secured to the front of said cradle in a position to receive filler material scooped from said container. 65

6. The combination with a shoe filler press 70 having filler leveling mechanism and an upright supporting member, of an apparatus for holding shoe filler material in a position adjacent to said leveling mechanism, said apparatus comprising a bracket secured to said supporting member, a 75 cradle for holding a container of filler material, said cradle being mounted on said bracket for pivotal movement about horizontal and vertical axes, positioning means carried by said cradle and engageable with said container to hold it 75

firmly in position for any position of adjustment of said cradle, means for locking said cradle in any selected position of adjustment, and a shelf secured to the front of said cradle in a position to receive filler material scooped from said container.

5. The combination with a shoe filler press having filler leveling mechanism and an upright supporting member, of an apparatus for holding 10 shoe filler material in a position adjacent to said leveling mechanism, said apparatus comprising a bracket secured to said supporting member, a yoke pivotally secured to said bracket, means for locking said yoke at any desired position of 15 adjustment about its pivotal support, a cradle for holding a container of filler material, said cradle being mounted on said yoke for pivotal movement about an axis at right angles to the pivotal axis of said yoke, and a shelf secured to the front 20 of said cradle in a position to receive filler material scooped from said container.

7. The combination with a shoe filler press having filler leveling mechanism and an upright supporting member, of an apparatus for holding 25 shoe filler material in a position adjacent to said leveling mechanism, said apparatus comprising a bracket secured to said supporting member, a cradle for holding a container of filler material, said cradle being mounted on said bracket for 30 pivotal movement about a horizontal and vertical

axis, a shelf pivotally secured to the front of said cradle in a position to receive filler material scooped from said container, and means for locking said shelf in any position of adjustment relative to said cradle.

9. The combination with a shoe filler press having filler leveling mechanism and an upright supporting member, of an apparatus for holding shoe filler material in a position adjacent to said leveling mechanism, said apparatus comprising 10 a bracket mounted for vertical movement along said supporting member, clamping means for locking said bracket in any selected position of adjustment relative to said supporting member, a yoke mounted on said bracket for pivotal 15 movement about a vertical axis, means for locking said yoke at any desired position of adjustment about said axis, an arm pivotally supported on said yoke to swing about a horizontal axis, means for locking said arm at any selected position relative to said yoke, a cradle mounted on 20 said arm, said cradle being constructed and arranged to receive and retain a container of filler material, a shelf pivotally secured to the front of said cradle in a position to receive filler material 25 scooped from said container, and means for supporting said shelf in any desired position of adjustment relative to said cradle.

CHAS. F. EATON. 30
